UNITED STATES PATENT OFFICE.

EDWARD B. GIBFORD, OF ADRIAN, MICHIGAN, ASSIGNOR TO HENRIE CLAUSS, OF FREMONT, OHIO.

STROPPING-MACHINE.

No. 821,712.

Specification of Letters Patent.

Patented May 29, 1906.

Application filed January 28, 1905. Serial No. 242,219.

To all whom it may concern:

Be it known that I, EDWARD B. GIBFORD, a citizen of the United States, residing at Adrian, in the county of Lenawee, State of Michigan, have invented certain new and useful Improvements in Stropping-Machines; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to new and useful improvements in stropping devices for razor and other blades; and it consists in the construction and arrangement of parts herein-after fully set forth, and pointed out particularly in the claims.

The objects of the invention are to provide simple and efficient means for turning the blade of the razor at the beginning of a stroke so that the edge of the blade will be automatically brought into contact with the stropping-surface and will stand in a direction opposite to that in which the blade is moved.

A further object is to provide means for automatically returning the blade-holder to an upright position when the apparatus is at rest.

A further object is to provide means for supporting the handle of the razor when the blade is in the holder in the operation of stropping.

The above objects are attained by the structure illustrated in the accompanying drawings, in which—

Figure 1 is an elevation showing my improved stropping device with a razor in position therein. Fig. 2 is a transverse section as on line 2 2 of Fig. 1. Fig. 3 is a transverse section as on line 3 3 of Fig. 1, showing by dotted lines the movement of the blade-holder. Fig. 4 is a view similar to Fig. 3, showing by solid lines the blade-holder swung to one side, so as to bring the edge of the blade into contact with the surface of the strop. Fig. 5 is a transverse section on line 5 5 of Fig. 1. Fig. 6 is an enlarged vertical section through one end of the blade-holder, the friction-roller, the gearing, and other parts, through the medium of which the swinging of the blade-holder is accomplished.

Fig. 7 is an enlarged view, in longitudinal section, through the blade-holder, showing the slideable spring clamping-arm which is adapted to support the handle of the razor. Fig. 8 is a fragmentary view in perspective of the spring-jaws at the end of said arm.

Referring to the characters of reference, 1 designates a U-shaped frame between the ends of which is journaled the friction-roller 2, which is made fast to its journal-pins 3. Fixed to and extending nearly the entire length of the frame 1 is a blade-holder 4, comprising diverging spring sides which are adapted to clamp between them the blade 5 of the razor, which is inserted endwise between said spring sides. Fixed upon one of the journal-pins 3 is a gear-wheel 6, which meshes with a like wheel 7, fixed to a short shaft 8, whose ends are journaled in the opposed plates 9 and 10, which are held together by the binding screws or bolts 11. The shaft 8 projects through the plate 10 and receives upon the end thereof the arm 12. This arm is provided in its upper end with a slot 13 and with a recess extending downwardly from said slot in which is seated the coiled spring 14. Fixed to and projecting from the frame 1 is a pin 15, whose outer end lies in the slot 13 in the arm 12.

In the operation of this device the friction-roller 2 is pressed upon the leather strop 16, and by means of the handle 17, which projects from and is secured in the plate 10, the device is moved longitudinally of the strop. At the inception of the movement in either direction the roller 2, because of its contact with the strop, will turn slightly, thereby turning the gears 6 and 7 and swinging the arm 12. The movement of said arm is imparted to the frame 1 and the blade-holder through the medium of the pin 15, which lies in the slot of said arm, whereby as the device is moved in one direction along the surface of the strop the frame and blade-holder, because of the interposed gearing, are swung in the opposite direction, causing the blade to move into contact with the surface of the strop, as shown in Fig. 4. At the termination of the stroke in one direction and the inception of the return stroke the friction-roller 2 is rotated slightly in the opposite direction, thereby swinging the blade-holder to the opposite side, as shown by dotted lines in Fig. 3. Because of the presence of the

coiled spring 14 the blade-holder is returned to an upright position whenever the pressure upon the strop is relieved, thereby preventing a possible cutting of the strop, as the blade is always raised from contact with the surface thereof whenever the device is arrested in the operation of stropping.

Lying within the blade-holder is a spring-arm 18, which is made to slide longitudinally of the holder and is confined in place by the rivet 19, (see Fig. 7,) which passes through a slot 20 in the bottom of the holder. At the outer end of said arm are the opposed spring-jaws 21, which are adapted to embrace the handle 22 of the razor. The purpose of said spring-arm, with its clamping-jaws, is to support the handle of the razor when stropping. In most razors the handle becomes loose upon the rivet which secures it to the tang of the blade, and if the handle were not supported it would fly around in the operation of stropping to such an extent as to materially interfere with the operation. Within the center of the spring-arm is a V-shape point 23, which when the arm is drawn outwardly engages the tang of the blade, so as to throw the end of the arm downwardly and present the jaws 21 in proper position to grasp the handle, as shown in Fig. 1. The adjustability of the spring-arm enables it to be drawn outwardly such distance as to accommodate any length of blade and handle, and when not in use may be shoved inwardly out of the way, as shown in Fig. 7.

Having thus fully set forth my invention, what I claim as new, and desire to secure by Letters Patent, is—

1. In a blade-stropping device, the combi-

nation of the movable blade-holder, the friction-roller and movable arm, gearing connecting said roller and arm, said arm having a slidable engagement with the blade-holder. 40

2. In a blade-stropping device, the combination with the blade-holder, a friction-roller journaled between the ends of the blade-holder, a pivoted arm, gearing connecting said roller and arm, a pin upon the blade-holder having a slidable engagement with said arm, and a spring in said arm engaging said pin. 45

3. In a blade-stropping device, the combination with the movable blade-holder, of a friction-roller, a gear-wheel thereon, a second gear-wheel meshing therewith, a shaft upon which said second gear-wheel is fixed, a movable arm fixed to the end of said shaft, said arm having a slot therein and a socket extending from said slot, a coiled spring seated in said socket, and a pin upon the blade-holder lying in said slot and engaging said pin. 55

4. In a stropping device, the combination of the blade-holder having a longitudinal slot in the bottom thereof, a friction-roller, means connected with said roller for swinging the blade-holder from side to side, a slidable spring-arm in the blade-holder, said arm having a rivet engaging in the slot in the bottom of the blade-holder and having jaws adapted to clamp the handle of the razor. 65

In testimony whereof I sign this specification in the presence of two witnesses.

EDWARD B. GIBFORD.
